D. H. GOODELL, OF ANTRIM, NEW HAMPSHIRE.

Letters Patent No. 102,934, dated May 10, 1870.

IMPROVED FORK FOR PEACH-PARERS.

The Schedule referred to in these Letters Patent and making part of the same

To all whom it may concern:

Be it known that I, D. H. GOODELL, of Antrim, in the county of Hillsborough and State of New Hampshire, have invented an Improvement in Peach-Parers; and I do hereby declare that the following, taken in connection with the drawings which accompany and form part of this specification, is a description of my invention sufficient to enable those skilled in the art to practice it.

My invention has reference to the construction of the peach-holding fork of a peach-paring machine.

In apple-paring machines the fork is generally made three-pronged, and the apple is pressed upon the fork regardless of any particular presentation of the apple, so long as the fork is carried centrally through the core, there being nothing to interfere with the entrance of the prongs.

With peaches, however, the same construction will not answer, because the prong points bring up against and are stopped by the peach-stone.

It is necessary, therefore, to spread the prongs far enough apart to straddle the stone or embrace it between them; but a three-pronged fork is not practicable for this purpose, and a two-pronged fork has been made, having a groove in the inner face of each prong; the opposite edges or sharp corners of the stone slipping into these grooves, and thus holding the peach securely during the paring operation.

Now this construction is efficient in holding the peach when the edges of the peach-stone fit into the forked grooves; but, if the peach-stone is too large or too small for the fork, or if the prong-grooves fail to slip over the edges, (and this they are very apt to do,) the peach will not be securely held.

The object of my invention is to so construct a fork as to insure its taking hold of and tightly embracing the stone, and this I accomplish by using a four-pronged fork, between which the stone cannot fail to enter and be held; and

My invention consists in combining, with a paring mechanism, a four-pronged fork, for the better adaptation of the machine to the paring of peaches.

The drawing represents a fruit-paring machine embodying my improvement.

A shows a plan of the machine.

B, a side view, and

C, an end view of the fork grasping a peach-stone.

a denotes the stationary gear-plate, having a segmental gear, b, into which meshes a pinion, c, on a shaft carrying a gear, d, which meshes into and drives

a pinion, e, on the fork-shaft e², the rotation of pinion e being effected by horizontal reciprocating movement of the handle f.

G denotes the paring-knife, fixed upon a suitable knife-rod, and held up to the surface of the fruit by a suitable spring. All these parts are shown arranged like the corresponding parts in a common and well-known parer, or may be relatively arranged in any other suitable manner, and need not be further described.

h denotes the fruit-holding fork, consisting of four prongs, i, preferably placed equidistant each from the adjacent prongs, and flaring slightly, if desirable.

Now, as the depressed line upon the surface of a peach indicates the line of the sharp corner or edge of the peach, (the two being in the same plane,) it will readily be seen that in pressing a peach upon the fork it can always be so guided that the stone cannot fail to enter the fork between the prongs, as seen at B and C, or with two prongs straddling one edge of the peach, and the opposite two the opposite edge, each two being equidistant from the edge between them, (the stone being thereby firmly grasped,) and of course securely holding the rotating peach under the pressing and cutting action of the knife; and it will be obvious that such a disposition of the forks affords the only practical construction for peach-paring, as no arrangement of three or two forks can be depended upon to thus clasp or grasp the stone.

The spring forks or wires, it will be seen, are inserted in the stock so as to be near to each other; they are then spread out from and near the stock, as shown, and then for the rest of their lengths are straight, and parallel, or nearly so, with each other. By means of this construction, and the use of four such prongs, each so bent, the peach-stone is not only firmly held at four points, but the bent portions also hold it steadily at its curved end; and the device is equally applicable, by reason of having the straight parts of the fork, for use in paring other fruit which is stoneless, as the straight prongs do not, like those which are curved from end to end, cut and destroy the fruit whilst being inserted in and withdrawn from it.

I claim a fork, having four separate spring prongs, which spread out from and near the stock, and are then straight, or nearly so, as shown and described.

D. H. GOODELL.
